SCRATCHING POST FOR CATS

Paul A. Borak, 600 Shepley Drive,
Glasgow Village, Mo. 65254

Filed June 15, 1973, Ser. No. 370,429

Term of patent 14 years

Int. Cl. D30—99

U.S. CL. D30—42

FIG. 1

FIG. 2

FIG. 3

FIG. 4

FIG. 5

FIG. 6

FIG. 7

FIG. 1 is a perspective view of a scratching post for cats showing my new design;

FIG. 2 is an elevational view;

FIG. 3 is a top plan view;

FIG. 4 is a bottom plan view;

FIG. 5 is a perspective view of a modified form of the scratching post for cats;

FIG. 6 is a top plan view thereof; and

FIG. 7 is a bottom plan view.

I claim:

The ornamental design for a scratching post for cats, as shown and described.
